UNITED STATES PATENT OFFICE

2,307,348

FASTENING DEVICE

Chester Sig Anderson, St. Charles, Ill.

Application April 14, 1941, Serial No. 388,386

2 Claims. (Cl. 85—29)

The present invention relates to a fastening device for attaching panels of plasterboard or the like upon a frame in such manner as to make provision for relative movement to the sheet of plasterboard with respect to other sheets and with respect to the studding or joist to which it is attached.

The natural thermal expansion and contraction of plasterboard is recognized. In addition it is well-known that studdings or joists made of wood are subject to considerable contraction and expansion, and in addition other causes such as uneven settling of the building frequently causes undue pressure upon the wallboard and the finished product which results in unsightly cracks and crevices.

It is the object of my invention to provide means of attachment which will permit a limited shifting of the panels to conform to the movement of the panels or the framework to which it is attached, at all times and particularly after the finish coats of plaster are applied to the panels of plasterboard.

A further object is to provide a more economical and durable means of attaching the panels to the studding or other support in the erection of modern low-cost buildings.

A still further object is to provide a combination of nail and cap which can be attached at the factory and which can be driven into place in one operation, thereby comparing very favorably in labor time in installing with the conventional nail used before this improved type of nail was thought of.

Further objects are to provide a construction of maximum simplicity, efficiency, economy, ease of assembly and operation, and such further objects, advantages and capabilities as will later more fully appear and are inherently possessed thereby.

The invention further resides in the combination, construction and arrangement of parts illustrated in the accompanying drawing, and while I have shown therein a preferred embodiment, it is to be understood that the same is susceptible to modification and change without departing from the spirit of my invention.

In the drawing:

Figure 1 is an isometric view of one of the elements of my novel fastening device.

Figures 2 and 3 are isometric views of such element provided with a cap for such element.

Figure 4 is an isometric view showing sections of wallboard or other siding secured in place by my novel fastening device prior to the applica-

tion of finish coats of plaster or other surface media.

Figure 5 is a view in horizontal cross-section taken on the lines 5—5 of Figure 4.

Figure 6 is an isometric view of a modified form of cap.

Referring more particularly to the disclosure in the drawing, sheets of plasterboard 1 or similar material are attached to studdings 2 and headers or foot rails of a frame as shown in Figure 4.

In operation, the nail 3 is driven through the plasterboard and into the wood frame at intervals of approximately eight inches. The nail 3 has a head 4 and a point 5 at the end opposite the head. Intermediate the point 5 and the head 4 is an enlarged hump 6 which is placed at sufficient distance from the head 4 to span the thickness of the plasterboard. The nail 3 is driven into position so that the head rests lightly against the outer surface of the panel of plasterboard 1. As the hump 6 which is larger than the diameter of the rest of the shaft of the nail, passes through the plasterboard, it creates an opening of considerably greater diameter than the diameter of the rest of the shaft and will allow considerable play between the relative position of the plaster panel and the framework.

After the nails 3 are driven home to hold the plasterboard, it is necessary to make provision against the binding effect of the finish coats of plaster which would otherwise bind the nail head 4 to the panel 1. I provide this by means of a cap 7 which has a cross-section slightly larger than the cross-section of the head of the nail to form a covering for the head of the nail. This cap has a plurality of wedge-shaped protrusions 8, each of which are driven into the plasterboard to hold the cap in place. The cap is also provided with flanges 9 which are adapted to bend around the edge of the nail head 4 at the fastening where such nails are made or at any time prior to driving the nail through the plasterboard. The cap is of sufficient diameter to permit limited movement of the head 4 within the cap 7 so that free play is allowed between the nail and the cap. The modified form of cap shown in Figure 6 is adapted to be applied to the nail after the nail has been driven into the studding. It is provided with flanges 10 to hold it in place over the nail head 4 and onto the plasterboard 1. It is to be observed that either form of cap which I show may be stamped from a single piece of metal. By having the nail and cap assembled in one unit, much labor in attach-

ing the wall board may be saved inasmuch as but one operation is required in driving the nail and cap home.

After the caps are fastened in place over each of the nails, a finish coat of one or two coats of plaster is applied to the panels, covering the panels 1 and the caps 7. I have found that it is preferable to have the crown of the cap slightly rounded to obviate the danger of being dislocated by the trowel when the plaster coat is added.

Experiments and tests have shown that with this invention the plasterboard and plaster are held to the framework securely but with sufficient yieldability with respect to lateral strain upon the plasterboard and plaster to prevent cracks in the plaster or to reduce the same to a minimum.

Having thus described my invention, what I claim as new and desire to secure as Letters Patent is:

I claim:

1. In a device of the class described, the combination of a nail having a shank, pointed at one end and provided with a head at the other end, an approximately flat cap of substantially greater area than and covering the head of the nail, and anchoring projections on the cap normally spaced from the periphery of the head to allow limited movement of the head within the plane of the cap.

2. In a device of the class described for attaching wall surfacing to a frame, a nail having an enlarged head, and an enlarged substantially conical shaped portion on the shank at a point intermediate the point and head of said nail to provide an opening in said wall surfacing larger than the diameter of said shank, and a substantially flat cap for said nail head provided with anchoring projections for attachment to said wall surfacing and permitting co-planar movement of said nail head within the confines of said cap.

CHESTER SIG ANDERSON.
